UNITED STATES PATENT OFFICE.

ALBERT H. RÖGER, OF PHILADELPHIA, PENNSYLVANIA.

WINDOW.

SPECIFICATION forming part of Letters Patent No. 375,000, dated December 20, 1887.

Application filed March 17, 1887. Serial No. 231,220. (No model.)

To all whom it may concern:

Be it known that I, ALBERT H. RÖGER, a subject of the Emperor of Germany, having resided in the United States one year last past 5 and declared my intention of becoming a citizen thereof, residing at Philadelphia, Pennsylvania, have invented a new and useful Improvement in Windows, which improvement is fully set forth in the following specification 10 and accompanying drawings, in which—

Figure 1 represents a face view, partly broken away, of a window, looking from the inside of an apartment embodying my invention. Fig. 2 represents a horizontal section 15 thereof in line $x-x$, Fig. 1.

Similar letters of reference indicate corresponding parts in the two figures.

My invention consists of a window formed of sliding sashes which are fitted to a hinged 20 frame, whereby the sashes, in addition to being adapted to raise and lower, may be opened after the manner of a door.

It also consists of a novel fastening for the window-frame.

Referring to the drawings, A represents a window-frame, which has raising and lowering sashes B B, the latter being provided with boxes, sash-weights, and cords, as usual with such sashes. The frame A is connected with 30 a frame, C, by means of hinges D, whereby the window may be opened and closed after the manner of a door, the frame C being stationary and set in the wall of the building.

It will be seen that the outside of the window is readily accessible by swinging the window inwardly, and the window may be entirely opened for purposes of light, air, and ventilation.

In order to fasten the window-frame I employ spring-pressed plugs E, having a rounded head, which are fitted in boxes F, secured to the frame C and appearing at the inner side thereof, and adapted to enter sockets or openings G in the face-plates H on the side stiles

of the window-frame A, said plates being 45 slightly inclined, so that during the operation of closing the window the plugs E yield and ride on said plates, and then drop into the sockets G, whereby the window-frame is held closed. 50

The plug E has a rounded head, so that when the sash is drawn inwardly the said plug is readily pressed back, so that it is free from the socket, thereby permitting the opening of the sash when desired. 55

I am aware that it is not new to construct a swinging window-frame having vertically-moving sashes therein; but I am not aware that the peculiar construction and arrangement of parts whereby the frame can either be 60 readily closed or opened, as herein shown and described, has ever been employed.

Having thus described my invention, what I claim as new, and desire to secure by Letters Patent, is— 65

1. In a combined sash and window-frame, a hinged window-frame having an inclined plate with socket therein, secured to one of the side stiles thereof, in combination with the spring-plug having a rounded head adapted to enter 70 said socket, said plug being secured in a box in an inclosing-frame for said hinged window-frame, substantially as and for the purpose set forth.

2. In a combined sash and window-frame, 75 the combination of the hinged window-frame A, having the raising and lowering sashes B B, and the inclined plate H, having the socket G therein, with the frame C, having the box F, with the spring-pressed plug E, the latter 80 having a rounded head adapted to enter the said socket G, substantially as and for the purpose set forth.

ALBERT H. RÖGER.
